COMBINATION WORKBENCH AND DRAWING
TABLE

James A. Swainbank, Flushing, N. Y.

Application April 20, 1951, Serial No. 222,040

3 Claims. (Cl. 312—316)

1

This invention relates to combination furniture and more particularly to an article of furniture that can be used as a table, a work bench or a drawing board.

It is among the objects of the invention to provide an improved article of combination furniture which, when closed, has the appearance of an ordinary furniture table and is neat and attractive and suitable for use in living quarters, and which can be opened in one way to provide a work bench and associated tool rack and in a different way to provide an inclined drawing board; which is solidly locked in any selected condition; and which is simple and durable in construction, economical to manufacture, and easy to change from one operative condition to another.

Other objects and advantages will become apparent from a consideration of the following description and the appended claims in conjunction with the accompanying drawings wherein:

Figure 1 is a perspective view of an article of combination furniture shown in one operative condition;

Figure 2 is a perspective view of the article of combination furniture shown in a different operative condition;

Figure 3 is a fragmentary cross sectional view on the line 3—3 of Figure 1;

Figure 4 is a fragmentary cross sectional view on an enlarged scale on the line 4—4 of Figure 1;

Figure 5 is a transverse cross sectional view on the line 5—5 of Figure 4;

Figure 6 is a fragmentary plan view of a top portion of the device showing a structural detail;

Figure 7 is a fragmentary top plan view also showing the structural detail illustrated in Figure 6, but with the parts in a somewhat different relative position;

Figure 8 is a transverse cross sectional view on the line 8—8 of Figure 2, but with the device shown in closed condition;

Figure 9 is a fragmentary cross sectional view on the line 9—9 of Figure 8; and

Figure 10 is a fragmentary perspective view showing the manner of attaching a tray to the device when used as a drawing board.

With continued reference to the drawings, the article of furniture comprises a frame of elongated rectangular shape which includes two frame side members 10 and 11 disposed in spaced apart and substantially parallel relationship to each other and two frame end members, one of which is indicated at 12, extending between the side members 10 and 11 at the respectively opposite

2

ends of the frame. A flat top 13, also of elongated, rectangular shape, is secured to one side of the frame and projects marginally beyond the side and end members of the frame, and table legs, as indicated at 14, 15, 16 and 17 are secured to the frame, one of each corner thereof and project from the frame in a direction away from the table top 13 and substantially perpendicular to the latter.

As illustrated in Figure 3 for the leg 16, the adjacent ends of the side member 10 and the end member 12 are spaced apart and are squared relative to the remainder of the members and the leg is of square cross sectional shape and is partly received between the spaced apart ends of the frame members 10 and 12 with one corner projecting inwardly of the frame. A brace 18 extends diagonally across the corner of the frame and is secured at its opposite ends to the frame members 10 and 12. This brace is spaced from the adjacent corner of the table leg 16 and is provided with an aperture substantially at its mid-length location and a lag screw 19 extends through the aperture in the brace and is threaded into the table leg 16 with its head bearing against the inner side of the brace to rigidly but detachably secure the table leg to the frame. The other table legs are of the same shape and are secured to the frame in the same manner.

The side members 10 and 11 of the frame are provided with mutually registering openings of elongated, rectangular shape and a drawer 20 is mounted in the frame at the under side of the top 13 and is slidable through the openings in the frame side members outwardly of either of the frame side members, as may be desired.

A box, generally indicated at 21, of elongated, rectangular shape is mounted on the table top 13 and has side members 22 and 23 disposed in spaced apart and substantially parallel relationship to each other, end members 24 and 25 and a top member 26 secured to one side of the frame provided by the side member 22 and the end members 24 and 25. The side member 23 is rigidly secured along one edge to the table top 13 adjacent one longitudinal edge of the table top and projects upwardly from the table top substantially perpendicular to the latter. The box top member 26 is hinged along one edge to the edge of the side member 23 remote from the table top 13 by suitable hinges, as indicated at 27, so that the box 21 can be siung upwardly and downwardly relative to the table top.

On the inner side thereof and within the area bounded by the side member 22 and end mem-

ber 24 the box top member 26 is provided with tool supports, such as the brackets 28 and 29 for supporting a saw, the row of spring clips 30 for supporting tools, such as hammers, screwdrivers, chisels, et cetera, and a cabinet 31 for containing tools, fasteners, and other articles.

The cabinet 31 may conveniently comprise two compartments 32 and 33 mounted in an elongated housing and pivotally connected at their outer ends to the housing, as indicated at 34 in Figure 5, so that the inner ends of these compartments can be swung inwardly and outwardly to render their contents accessible or to close them into the casing. A spring detent, as indicated at 35 in Figure 5, may be provided at the inner end of each compartment to releasably latch the compartment in closed condition.

Stays 37 and 38 are disposed at the inner sides of the end members 24 and 25 respectively and each stay is pivotally connected at one end to the associated end member substantially at the mid-length location of such end member. At its other end each stay is provided with a rectangular notch 39 which closely receives the rectangular cross sectional shape of the side member 23 of the box 21 and hooks 40 and 41 project inwardly of the side member 23, one near each end thereof.

The notches 39 in the free or distal ends of the stays 37 and 38 receive the fixed side member 23 and the hooks 40 and 41 engage the outer edges of the stays to lock them in engagement with the fixed side member. The box structure will then be securely held in substantially vertical position relative to the table top and the table top may now be used as a work bench while the box structure will constitute an associated tool rack.

The free or distal end portions of the stays 37 and 38 can swing past the outer ends of the corresponding hooks 40 and 41 when the box structure is raised to upright position and, after the box structure has been brought to upright position, the stays are swung inwardly away from the adjacent end members 24 and 25 and into engagement with the corresponding hooks.

An eccentric cam 42 is pivotally mounted on the inner side of the end member 24 adjacent the pivotal connection between this cam member and the stay 37 and a similar cam, not illustrated, is mounted on the inner side of the end member 25 to cooperate with the stay 38. With the box structure 21 in an inclined position relative to the table top, as illustrated in Figure 2, and with the free additional ends of the stays 37 and 38 resting upon the upper surface of the table top 13, the cams may be rotated to bear upon the upper edges of the stays and support the box structure at selected positions of inclination, so that its top member can be used as a drawing board.

A molding strip 43 extends along the edge of the box top member 26 adjacent the fixed side member 23 and is held onto the top member 26 by screws threaded into the corresponding edge of the top member and extending through transversely elongated slots in the molding strip so that the molding strip can be raised slightly above the top surface of the top member 26 to provide a ledge to prevent paper and drawing instruments from sliding off of the top member of the box structure while the latter is being used as a drawing board.

The pins 44 which pivotally connect the stays 37 and 38 to the end members 24 and 25 of the

box structure are longer than the thickness of the stays, so that the stays can be moved outwardly along these pins and pass by the corresponding eccentric cams to bring the stays to a position between the cams and the under surface of the top member 26 to thereby place the stays in an out of the way position for closing the box structure onto the table top, as illustrated in Figure 8.

10 The fixed side member 23 of the box structure is provided at one end with a rectangular notch 45 adjacent the upper surface of the table top 13 and a tray 46 in the form of a flat, rectangular plate has adjacent one corner a groove 47 extending longitudinally of the plate substantially parallel to one edge thereof. When the grooved portion of the tray 46 is received in the notch 45 in the member 23 the tray is firmly supported on the table substantially parallel to the table top, as illustrated in Figure 2, and projects outwardly both laterally and longitudinally from the member 23, so that this tray can be conveniently used to hold material, such as pencils, ink, paint and crayons while the top member 26 of the box structure is being used as a drawing board.

15 The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

20 What is claimed is:

25 1. An article of combination furniture comprising a table having a flat top, a flat box structure including spaced apart and substantially parallel side members one of which is secured along one edge to said table top along one edge of the latter and upstands substantially perpendicularly from the table top, end members rigidly secured each at one end to the other side member at respectively opposite ends of the latter and extending perpendicularly from said other toward said one side member, and a box top rigidly secured along one side edge and its end edges to said other side and said end members 30 and hinged along its other side edge to said one side member along the edge of the latter remote from said table top, said side and end members all being disposed at the same side of, and said other side and end members extending perpendicularly from, said box top, hooks secured to said one side member one near each end thereof, and stays pivotally secured each at one end, one to each of said end members intermediate the length of the latter, said stays having their distal ends receivable one in each of said hooks and having notches in their distal ends receiving said one side member to support said box structure in upstanding position substantially perpendicular to said table top.

35 2. An article of combination furniture comprising a table having a flat top, a flat box structure including spaced apart and substantially parallel side members one of which is secured along one edge to said table top along one edge of the latter and upstands substantially perpendicularly from the table top, end members rigidly secured each at one end to the other side member at respectively opposite ends of the latter and 40 extending perpendicularly from said other toward

said one side member, and a box top rigidly secured along one side edge and its end edges to said other side and said end members and hinged along its other side edge to said one side member along the edge of the latter remote from said table top, said side and end members all being disposed at the same side of, and said other side and end members extending perpendicularly from, said box top, hooks secured to said one side member one near each end thereof, stays pivotally secured each at one end one to each of said end members intermediate the length of the latter, said stays having their distal ends receivable one in each of said hooks and having notches in their distal ends receiving said one side member to support said box structure in upstanding position substantially perpendicular to said table top, said stays being also adapted to rest at their distal ends on said table top at locations spaced from said one side member, and eccentric cams pivotally mounted one on each of said end members and respectively engaging said stays to adjustably support said box structure at selected angles of inclination relative to said table top.

3. An article of combination furniture comprising a table having a flat top, a flat box structure including spaced apart and substantially parallel side members one of which is secured along one edge to said table top along one edge of the latter and upstands substantially perpendicularly from the table top, end members rigidly secured each at one end to the other side member at respectively opposite ends of the latter and extending perpendicularly from said other toward said one side member, and a box top rigidly secured along one side edge and its end edges to said other side and said end members and hinged

along its other side edge to said one side member along the edge of the latter remote from said table top, said side and end members all being disposed at the same side of, and said other side and end members extending perpendicularly from, said box top, hooks secured to said one side member one near each end thereof, stays pivotally secured each at one end one to each of said end members intermediate the length of the latter, said stays having their distal ends receivable one in each of said hooks and having notches in their distal ends receiving said one side member to support said box structure in upstanding position substantially perpendicular to said table top, said stays being also adapted to rest at their distal ends on said table top at locations spaced from said one side member, eccentric cams pivotally mounted one on each of said end members and respectively engaging said stays to adjustably support said box structure at selected angles of inclination relative to said table top, and tool supports secured to said box top at the side thereof at which said side and end members are disposed.
